UNITED STATES PATENT OFFICE.

GUSTAVOS HEIDEL, OF ST. LOUIS, MISSOURI.

AUTOMATIC CAR-BRAKE.

SPECIFICATION forming part of Letters Patent No. 274,767, dated March 27, 1883.

Application filed January 22, 1883. (No model.)

To all whom it may concern:

Be it known that I, GUSTAVOS HEIDEL, of the city of St. Louis, in the State of Missouri, have invented a certain new and useful Improvement in Automatic Car-Brakes, of which the following is a full, clear, and exact description, reference being had to the accompanying drawings, forming part of this specification, and in which—

10 Figure 1 is a vertical section of one end of a car with my improvement attached. Fig. 2 is a bottom view of same. Figs. 3, 4, 5, and 6 are enlarged detail views illustrating different parts, as referred to hereinafter.

15 My invention relates to a car-brake that is automatic in its operations; and my invention consists in certain novel features hereinafter fully described and claimed.

Referring to the drawings, A represents part 20 of a car-body, and B the draw-bar, connected to the body in the usual way, with a spring behind it, so that it has a slight endwise movement.

CC' represent the brake-bars suspended from 25 beneath the car in the usual manner and provided with the brake-shoes. The brake-beam C' is connected to a lever, D, at D', not far from one end of the lever, by a rod, C², and the brake-beam C is connected to this same lever, 30 D, at D², close to the end, by a rod, C³. The other end of the lever D is connected by a rod, C⁴, to the outer end of a horizontal arm, E, on the lower end of a vertical rock-shaft, F, supported by hangers G G', secured to the timbers H, between which the draw-bar works, 35 (see Fig. 5,) the shaft having a collar, I, and a pin, I', as shown, which hold it from dropping out. Just above the collar I the rock-shaft has rigidly secured to it a disk, J, with 40 pins J' projecting upward from or near its periphery, as shown in Figs. 5 and 6.

K represents a plate (see Figs. 2, 3, 4, 5, and 6) pivoted by its outer end to the draw-bar, as shown in Figs. 3 and 4. It, being secured 45 beneath the draw-bar, is supported by a strap, L, secured to the timbers H. Its inner or free end has an opening, K', sufficiently large to admit both of the pins J' when the plate is parallel with the draw head or bar. On one 50 side of the opening K' is a notch, K², facing outward, and on the other side is a notch, K³,

facing inward. Now, it will be understood that, if the plate is forced to one side, as hereinafter described, until the notch K³ engages with its pin on the disk J, and then the draw-bar forced back, carrying the plate K with it, the shaft F will be rocked, thus operating the brakes; and, likewise, it will be understood that if the draw-bar is compressed, and then the plate moved in the other direction until the notch K² engages with its pin on the disk J, and then the draw-bar and plate pulled out, the shaft will be rocked in the same direction, applying the brakes. The notches of the plate K are automatically engaged with the pins on the disk by the following means:

L² represents a rock-shaft secured to the bottom of the car by suitable brackets, L³, and having its outer end turned down, forming a crank, L⁴, which is connected to the free end of the plate K by a suitable rod, L⁵. (See Fig. 5.) Some distance from this end of the shaft it is provided with an arm, M, which is connected by a rod, M', to the outer end of a crank, N², on a vertical shaft, N', journaled to the bottom 75 of the car. A series of deflectors, O O' O² O³, (see Fig. 2,) having at their intersection a gate or valve, N, which is capable of opening in either direction, as shown, according to the direction in which the train is moving, are secured to the bottom of the car. When the train is standing still the gate is held closed by a spring, O⁴. (See Fig. 2.)

P are stop-pins to limit the opening of the gate.

The deflectors or air-chutes are made of sheet-iron, being closed at their backs to prevent side winds from having any effect on the gate. The gate might be pivoted to the bottom of the car and the deflectors dispensed with; but 90 I prefer to use them.

The operation is as follows: Supposing the car to be going forward, the draw-bar would be in its outer position, as shown in Fig. 2, and the gate would be opened by the air, as shown, 95 which would rock the shaft L², pushing the free end of the plate K over until the notch K³ would be behind its pin on the disk J. Then, supposing the engine to be reversed, the draw-bar would be pushed in, applying the brakes, as described, 100 and, as soon as the train comes to a standstill and the draw-bar allowed to assume its natu-

ral position, the gate will be closed by the spring O⁴ and bring the plate K back parallel with the draw-bar, so as not to be engaged by either pin on the disk J. Now, supposing the car to be backed, the draw-bar will be pushed in, the gate opened forward by the air, and the bar or plate K pulled over by the rock-shaft L² until the catch K² is behind its pin on the disk J. Then, the engine being reversed, the draw-bar is pulled out, applying the brakes, as described, and when the train stops and the pressure is relieved from the draw-bar the valve or gate closes, operating the plate K, as already described.

15 I claim as my invention—

1. In a car-brake, a plate secured to the draw-bar by one end, and provided with notches at the other end for engaging with pins on a disk which is secured to a rock-shaft connected by suitable means with the brake-bars, in combination with a suitable device for engaging the notches of the plate with the pins of the disk, whichever way the car is moving, substantially as shown and described.

25 2. In a car-brake, the combination of a gate pivoted to the bottom of the car and adapted to be opened either way, according to the di-

rection in which the car is moving, a horizontal rock-shaft secured beneath the car, a plate secured to the draw-bar by one end and provided with notches at the other end, and suitable means for connecting the horizontal rock-shaft with said gate and plate, as set forth.

3. A gate having a suitable spring to close it when the pressure is relieved from the draw-bar, in combination with a horizontal rock-shaft secured beneath the car, a plate secured to the draw-bar by one end and provided with notches at the other end, and suitable means for connecting the horizontal rock-shaft with 40 said plate and gate, as set forth.

4. A gate pivoted to the bottom of the car and having a deflector or air-chute, in combination with a horizontal rock-shaft secured beneath the car, a plate secured to the draw-bar 45 by one end and provided with notches at the other end, and suitable means for connecting the horizontal rock-shaft with said plate and gate, as set forth.

GUSTAVOS HEIDEL.
